DESIGN FOR A SHAVING MACHINE

Michael Annick, Scranton, Pa., assignor to F. Wesel Manufacturing Company, Scranton, Pa.

Application February 6, 1934, Serial No. 50,649

Term of patent 14 years

To all whom it may concern:

Be it known that I, Michael Annick, a citizen of the United States, residing at 617 Harrison Avenue, in the city of Scranton, county of Lackawanna, State of Pennsylvania, have invented a new, original, and ornamental Design for Shaving Machines, of which the following is a specification, reference being had to the accompanying drawing, forming part thereof.

The figure is a perspective view of a shaving machine, showing my new design. The opposite side of the machine is the same as shown, with the exception of the treadle, door panel and motor control switch.

I claim:

The ornamental design for a shaving machine, as shown and described.

MICHAEL ANNICK.
